UNITED STATES PATENT OFFICE.

FREDERICK D. SWEET, OF CLEVELAND, OHIO, ASSIGNOR TO INSTANT HOT PRIMER COMPANY, A PARTNERSHIP COMPRISING FREDERICK D. SWEET AND HENRY GROMBACHER, OF CLEVELAND, OHIO.

ENGINE-PRIMING DEVICE.

Application filed March 9, 1918. Serial No. 221,393.

To all whom it may concern:

Be it known that I, FREDERICK D. SWEET, a citizen of the United States, residing at Cleveland, in the county of Cuyahoga and 5 State of Ohio, have invented a certain new and useful Improvement in Engine-Priming Devices, of which the following is a full, clear, and exact description.

This invention relates to a device which 10 is adapted for use in connection with an internal combustion engine, more particularly an internal combustion engine which forms a part of a motor vehicle.

The purpose and object of the invention 15 is to provide a device which will inject a quantity of hot liquid fuel into the cylinders of an engine at the time of starting, thereby to provide in the cylinders an ignitable priming mixture which will enable the engine to 20 be started with ease.

A further purpose of the invention is to so mount the device upon the motor vehicle that the same shall easily be accessible from the seat of the driver of the car.

25 Generally speaking, the invention may be said to comprise the elements and combinations thereof set forth in the accompanying claim.

Reference should be had to the accompanying drawings forming a part of this specification in which Fig. 1 is an elevation with portions in section showing the application of the device of my invention to a motor vehicle and the engine thereof; Fig. 2 30 is a top plan view of a portion of the device; Fig. 3 is an elevation with portions in section of a portion of the device; and Fig. 4 is a sectional elevation of a portion of the device.

40 At the time of starting an internal combustion engine, particularly when the engine is cold, it is difficult to secure an ignition in the cylinders of the engine because of this cold condition of the engine.

45 Heretofore it has been the common practice to introduce fuel into the cylinders of the engine by means of priming cups and analogous devices. All of such devices with which I am familiar, have been located upon

the engine itself and have in most instances 50 required the operator to lift the hood so as to gain access to the priming cups in the operation of priming.

In the device forming my invention, the operating portions of the device are located 55 upon the dash-board of the motor vehicle or in some other convenient place so that a charge of liquid fuel may be delivered to the cylinders of the engine without the necessity of the driver leaving his seat. 60

Referring to Fig. 1, the engine of the motor vehicle is indicated at 1, and has the usual manifold 2. Attached to the manifold is a coupling member in the present instance an elbow 3, which at its lower end 65 has a jet 4. This jet may, if desired, have a restricted opening so that the liquid fuel passing through the same into the manifold may be injected or jetted thereby producing a spray of fluid fuel which is more easily 70 ignited than a body of fuel.

Secured to the coupling member 3 is a pipe section 5. This pipe section is made of material which is electrically an insulating material for purposes which will later 75 appear.

Secured to the pipe 5 is a conducting pipe 6 which is secured to a fuel dispensing container 7. In the present instance the fluid dispensing container is a pump, but it is entirely possible to utilize my invention without necessarily employing a pump. Therefore, a pump is but one form, which the container 7 may be made to assume. 80

The member 7 at one end thereof is formed 85 with an outlet passage 8 which communicates with the pipe 6. The passage 8 communicates with the chamber 9 of the member 7, and within this chamber there is located a piston 10 which is operated by 90 means of a piston rod 11 which terminates in a handle 12 by which the piston is operated.

Within the chamber 9 there is a spring 95 13 which normally presses the piston 10 toward the extreme end of the chamber 9 and in operating the piston 10, the piston is moved against the action of the spring,

which spring subsequently returns the piston to the end of the chamber 9.

In the body of the member 7 there is also a passage 14 which communicates with an exterior pipe 15, this pipe being preferably connected with the gasoline system of the motor vehicle so that when the piston 10 is operated, a supply of fluid fuel will be drawn into the chamber 9, and subsequently forced out through the passageway 8 to the pipe 6.

In order to effect this operation I employ a check valve 16, located in the passageway 14, and a check valve 17 located in the passageway 8. As will be seen from the drawing, these check valves operate in such fashion that as the piston 10 is withdrawn from the position shown in Fig. 3, fluid fuel will be sucked past the check valve 16 into the chamber 9, and when the piston 10 moves, returns to the position shown in Fig. 3. The fluid fuel which is within the chamber 9 is expelled through the passageway 8 past the check valve 17.

Within the pipe 5 there is a wire 18. This wire is made of material which is more or less resistant to the passage of the electric current through the same, so that as current is caused to pass through the wire, the wire becomes heated and the heat thus produced is absorbed by the fluid fuel passing through the conduit 5 around the wire 18.

While I have shown the heating element 18 as a single wire, it will be apparent that other forms than that here shown may be used with equal facility.

The electrical element 18 at one end bears against the pipe 6, which pipe is of a metal substance and a conductor of electricity. At the opposite end the element 18 is connected and attached to the member 3 which is also of metal, which is a conductor of electricity.

Inasmuch as the member 3 is connected to the manifold 2, it will be apparent that the wire 18 is in electrical connection with the metallic parts of the motor vehicle or grounded.

Adjacent one end of the member 7 there is an insulated block member 20 which carries a contact 21, and a contact 22. These contacts are spaced from each other so that normally there is no passage of current between them. The contact 21 is by a suitably insulated electrical conductor 22, connected with the electrical system which forms a part of every motor vehicle, while the contact 22 is grounded with respect to the member 7 which is of metal as is also the stem of the contact member 25 so that there is a path for an electric current from the contact 22 through the body of member 7, through pipe 6 to the wire 18.

Mounted upon the member 7 is a conical shaped contact member 24. This contact

member has a stem 25 which is surrounded by a spring 26. The stem 25 is guided in its movement through an opening in a member 27 mounted upon the member 7. The rod 25 extends through the contact 24 and through an opening in the flange or extension 7^a 70 formed upon the body 7. The rod 25 is at its end formed with an extension or ring-like portion 28 which encircles the rod 11 and is beneath the handle or operating portion 12. The action of the spring 26 is such as to 75 tend to force the contact member 24 between the terminals 21 and 22, but such action is restrained due to the engagement of the portion 28 with the handle 12.

It will be apparent that when the handle 80 12 is moved outwardly, the action of the spring 26 will move the contact member 24 into engagement with the terminals 21 and 22, thereby closing an electric circuit through the wire 18 which will generate heat in a 85 manner which will be well understood.

It will also be clear that in pulling the handle 12 outwardly, the chamber 9 will become filled with fluid fuel, and when the handle 12 is released, the action of the spring 90 13 will be to cause the expulsion of the fluid fuel through the pipe 6, the conduit 5, the member 3, and so into the manifold of the engine, and as the fluid fuel passes through the conduit 5 it will become heated so that 95 upon its delivery to the manifold of the engine it is in highly heated condition, and therefore in better condition to ignite.

The contact 24 has but a limited movement, as will be apparent, and therefore the contact remains in engagement with the terminals 21 and 22 until the handle 12 has substantially returned to its initial position when the engagement of the handle with the portion 28 of the stem 25 pushes the contact 24 out of engagement with the terminals 21 and 22, thereby breaking the electric circuit through the wire 18.

As shown in the drawing, the member 7 is mounted upon the dashboard of the motor vehicle, the flange 7^a serving as a means by 110 which the member 7 may be thus attached.

Having described my invention, I claim:

The combination with an internal combustion engine, of a receptacle adapted to contain fluid fuel, a movable member controlling the passage of fuel from said receptacle, means for returning the movable member to its initial position after being moved, a conduit connecting the receptacle with the engine, a portion of said conduit being composed of electrically non-conducting material, a heating element within the said non-conducting portion of a conduit, the ends of said heating element being connected with the conduit upon either side of the non-conducting portion, a switch controlling the passage of current through the conduit, and 125

the heating element, said switch being spring pressed and having a portion which engages with the aforesaid movable member whereby the switch is held in non-operative position

5 under normal conditions, the movement of the movable member permitting the switch to move to operative position to close the

circuit through the heating element, the movement of the movable member to its initial position moving the switch to inoperative position. ¹⁰

In testimony whereof, I hereunto affix my signature.

FREDERICK D. SWEET.
